GUN-BARREL.

1,089,079.

Specification of Letters Patent.

Patented Mar. 3, 1914.

Application filed December 19, 1911. Serial No. 666,670.

To all whom it may concern:

Be it known that I, HEINRICH RABBA, residing at Essen-Rüttenscheid, Germany, a subject of the Emperor of Germany, have 5 invented a certain new and useful Improvement in Gun-Barrels, of which the following is a specification.

This invention relates to a gun barrel separable into a bore-tube and a jacket, together with its appurtenant slide, and has for its purpose to so produce such an arrangement that the assembling and disassembling can take place with greatest practicable readiness and convenience.

15 In the accompanying drawing, Figure 1 shows a longitudinal section of the parts which come into consideration in one illustrative embodiment of the subject matter of the invention; and Figs. 2 to 6 are sections taken respectively on the lines 2—2, 20 3—3, 4—4, 5—5, and 6—6 of Fig. 1, all looking from the right.

The gun barrel comprises a bore-tube A and a jacket B, which latter incloses the rear portion of the bore-tube only, and simultaneously provides the breech of the gun barrel. A bayonet joint serves for connecting the bore-tube with the jacket, which bayonet joint consists in a known manner of four 25 rows of annular sector-shaped ribs a^1 , mounted on the bore-tube, as well as corresponding ribs b^1 and grooves b^2 of the jacket (Figs. 1, 4 and 5). On the jacket is arranged a horn b^4 (Figs. 1 and 6) which is 30 designed for connecting the gun barrel with the recoil brake and the recuperator.

The gun barrel rests upon its slide C which projects beyond the muzzle of the bore-tube, but terminates considerably in 40 advance of the rear end of the jacket (at c^5 , Fig. 1). The slide C serves together with the jacket B, for guiding the gun barrel upon the slide track carrier of the gun, in a manner well known and which, therefore, 45 need not be disclosed in the drawing. The slide and jacket are provided, to this end, with guiding ribs c^1 (Figs. 1 to 5) and b^3 (Figs. 1 and 6). The bore-tube is provided beneath the muzzle, with an attachment a^2 which carries a ledge a^3 (Figs. 1 and 2) 50 directed toward the breech of the gun barrel. The ledge a^3 engages beneath a ledge c^2 of the slide. The ledges a^3 and c^2 are preferably curved concentric to the axis of 55 the bore of the gun barrel. The bore-tube

carries further, an attachment a^4 (Figs. 1 and 3), which engages in a corresponding recess c^3 of the slide C. Furthermore, there is provided on the rear end face of the slide C, a ledge c^4 (Figs. 1 and 6) which engages 60 a groove b^5 of the jacket. The groove b^5 and the ledge c^4 run concentrically to the axis of the bore of the gun barrel. Finally, in an attachment b^6 (Figs. 1 and 6), arranged on the upper side of the jacket, there 65 is mounted, rotatably but non-slidably, with its axis transverse to the axis of the bore of the gun barrel, a bolt D, which carries a hand grip d^1 (Fig. 1) and is provided with a plurality of ribs d^2 which extend transversely to the rotating axis of the bolt and are designed to enter into engagement with the grooves a^5 of the bore-tube. The ribs d^2 are so arranged that they will attain disengagement with the grooves a^5 , when the bolt 70 D has been rotated 180° from the position illustrated in the drawing.

In assembling the gun barrel, one proceeds in the following manner: First the bore-tube is placed upon the slide which has 80 been incompletely shoved upon the slide track carrier, until the ledge a^3 engages beneath the ledge c^2 and the attachment a^4 enters the recess c^3 . Hereupon, the jacket B, with the horn b^4 deflected 45° relatively to 85 its position shown in Fig. 6, is placed upon the bore-tube from behind, and for producing the above mentioned bayonet joint, is rotated relatively to the bore-tube. During 90 this movement, the ledge c^4 engages with the groove b^5 of the jacket. After the bolt D has finally been rotated to the locking position, in which the ribs d^2 prevent the jacket B from rotating relatively to the bore-tube A, the slide, together with the gun barrel, is 95 shoved completely upon the slide track carrier, and connection of the brake and recuperator with the horn b^4 is made. In assembled condition, the parts assume the position shown in the drawing. In this position, the gun barrel is secured against lifting from the slide C, on the one hand, by the ledges a^3 and c^2 , and on the other hand, by the engagement of the ledge c^4 in the groove b^5 of the jacket, and secured against 100 rotation and displacement upon the slide, by the attachment a^4 .

The method of disassembling the gun will be obvious from the foregoing and requires 110 no explanation.

It should be observed that the disclosed manipulation in assembling the gun, and the corresponding manipulation in taking down the gun can be carried out by the serving crew without leaving their places behind the shield of the gun, that is to say, the cover.

I claim:—

1. A separable gun barrel comprising a tube, a jacket and a slide, supporting means on said tube and slide leaving the rear end of the tube unsupported, and securing means on said tube and slide preventing turning and longitudinal displacement of said tube relative to said slide, the jacket being separable from said tube and slide and adapted to be pushed over the free rear end of the tube secured to the slide.
2. A separable gun barrel comprising a tube, a jacket and a slide, supporting means on said tube and slide, leaving the rear end of the tube unsupported, and securing means on said tube and slide preventing turning and longitudinal displacement of said tube relative to said slide, said securing means comprising interengaging ledges on slide and tube at the muzzle and a lug and a recess therefor on tube and slide respectively at the middle of the tube, the jacket being separable from said tube and slide and adapted to be pushed over the free rear end of the tube secured to the slide.
3. A separable gun barrel comprising a tube, a jacket and a slide, securing means on said tube and slide situated at the muzzle and the middle of the tube leaving its rear end unsupported, said securing means preventing turning and longitudinal displacement of said tube relative to said slide, a bayonet joint adapted to secure jacket and tube together, locking members on jacket and tube respectively for preventing turning of said jacket relative to said tube, holding down members on said jacket and said slide respectively comprising interengaging annular ledges concentrically arranged around the axis of the gun barrel.
4. A separable gun barrel comprising a tube, a jacket and a slide, securing means on said tube and slide situated at the muzzle and the middle of the tube leaving the rear end of the tube unsupported, said securing means preventing turning and longitudinal displacement of said tube relative to said slide; said securing means comprising inter-

engaging ledges on slide and tube at the muzzle, and a lug and a recess therefor on tube and slide respectively at the middle of the tube; a bayonet joint adapted to secure said jacket and tube together, male and female locking members on jacket and tube respectively for preventing turning of said jacket relative to said tube; holding down members on said jacket and the rear end of said slide respectively, comprising interengaging annular ledges concentrically arranged around the axis of the gun barrel; whereby the assembling of the gun barrel is accomplished by first laying the tube on the slide permitting said securing means to engage, by thereupon pushing the jacket over the free rear end of the tube and turning it to secure the bayonet joint and simultaneously engaging the holding down members, and lastly by operating said male locking member to hold said jacket from turning.

5. A separable gun barrel comprising a bore-tube, a jacket and a slide, a bayonet lock adapted to secure jacket and bore-tube together; a ledge on said bore-tube adjacent the muzzle; a second ledge on said slide made to interlock with the bore tube ledge; a third ledge on the rear end of the slide; a groove on the jacket engaging said third ledge; said ledges and groove adapted to hold down said bore-tube and jacket on said slide; a lug on said bore-tube; a cut in said slide adapted to engage said lug and thereby to prevent any axial or rotary movement of the bore-tube relative to the slide; a housing on the jacket situated on top thereof; a collar bolt seated in said housing transversely to the axis of the bore and adapted to rotate in said housing; a plurality of parallel collars on one side of said bolt; a handle, accessible from the outside on said bolt, adapted to turn said bolt about 180° from locking to unlocking position; a plurality of grooves on said bore tube constructed to coöperate with said bolt collars to prevent the turning of said jacket relative to the bore-tube.

The foregoing specification signed at Bar-
men, Germany, this 28th day of November, 1911.

HEINRICH RABBA. [L. s.]
In presence of—
HELEN NUFER,
A. NUFER.
